D. H. Baldwin Company, Cincinnati, Ohio, a corpora-
tion of Ohio

Filed Nov. 24, 1965, Ser. No. 88,204

Term of patent 14 years

(Cl. D56—9)

Fig. 1

Fig. 2

Fig. 3

FIGURE 1 is a front elevational view of a piano case embodying my new design.

FIGURE 2 is a side elevational view thereof.

FIGURE 3 is a partial side elevational view with a part broken away, showing the music desk and its supporting means in cross section.

The side of the piano case not shown is the same as the side shown. The dominant features of my design reside in the parts shown in solid lines. The conventional keyboard is fragmentarily shown by means of broken lines and is continuous across the piano as indicated by the dash-dot lines.

I claim:

The ornamental design for a piano case, substantially as shown and described.
